tions of the cord 31 and will thus be arrested and will not be allowed to roll wildly over the room.

It is thus seen that I have provided a golf-putting apparatus which can be used indoors, which can be used in association with a carpet or rug if desired, or by projecting the board 12 down to the floor line and adjusting the rear edge of the board 12 to be flush with the front edge of the sheet or board 23, the apparatus could be used without the aid of a carpet or rug if desired.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a golf putting apparatus, a pair of bars disposed in spaced relation to each other, means secured between the bars for holding them in fixed relation, a pair of bars pivotally secured on the proximate surfaces of the first two bars and having a sheet member secured to their upper surfaces, the lateral edges of the sheet member overlapping the upper edges of the two first-named bars, the sheet member having a hole therethrough, one end of the first-named bars being sloped to a point and adapted to be inserted beneath the edge of a carpet, rug and the like and a flexible member secured to the rear ends of the two first-named bars and having anchoring members secured to the free ends thereof so that the flexible member may be extended laterally on each side of the golf-putting device and in spaced relation to the front portion thereof.

2. A golf-putting apparatus comprising a framework, a sheet member pivotally mounted in the framework and being adjustable at its front edge relative to the framework and having

a hole therethrough through which golf balls may drop, the front end of the framework sloping to a point and being adapted to be inserted beneath the edge of a carpet, rug and the like, the sheet member being adjustable relative to the framework so as to cause its front edge to coincide with the edge of the carpet, rug and the like, and a flexible member secured to the rear portion of the framework and having its free ends projecting forwardly and in diverging relation to the front end of the framework.

3. In a golf putting practice apparatus, a framework having an inclined surface at one end thereof up which projected golf balls are adapted to roll and onto which one edge of a rug may be placed, a sheet member disposed over the framework having its front edge in close proximity to the rear edge of the inclined surface and said sheet member being provided with a hole through which balls rolling up the inclined surface onto the sheet member may fall, means for pivotally supporting the sheet member in the framework for adjusting the height of the front edge of the sheet member relative to the framework, so that its upper surface will be flush with the upper surface of the rug disposed on the inclined surface.
